US00D999446S

(12) **United States Design Patent** (10) **Patent No.:** **US D999,446 S**
Woodruff et al. (45) **Date of Patent:** **** Sep. 19, 2023**

(54) CONTAINER FOR DRY PRODUCTS	825,263 A	7/1906	Alexander et al.
(71) Applicant: AMVAC CHEMICAL CORPORATION , Newport Beach, CA (US)	861,355 A	7/1907	Brower
	868,300 A	10/1907	Sohner et al.
	924,099 A	6/1909	Nelson
	931,882 A	8/1909	Martin
(72) Inventors: Keith Woodruff , Mountainside, NJ (US); Brian Kaltner , Fairfield, NJ (US); Richard L. Rice , Collierville, TN (US)	2,794,407 A	6/1957	Wist et al.
	2,823,829 A	2/1958	Frater
	3,459,160 A *	8/1969	Rice F22B 1/06 126/400
(73) Assignee: AMVAC CHEMICAL CORPORATION , Newport Beach, CA (US)	4,009,668 A	3/1977	Brass et al.
	4,497,265 A	2/1985	Hood et al.
	4,521,908 A	6/1985	Miyaji et al.
	4,522,340 A	6/1985	Gandrud
	4,529,073 A	7/1985	Lewis
	4,570,858 A	2/1986	Binter et al.
	4,611,606 A	9/1986	Hall et al.
	4,691,645 A	9/1987	Anderson
	4,705,220 A	11/1987	Gandrud et al.
	4,895,106 A	1/1990	Barnes
	4,896,615 A	1/1990	Hood, Jr. et al.
	4,917,304 A	4/1990	Mazzei et al.
	4,971,255 A	11/1990	Conrad
	5,024,173 A	6/1991	Deckler
	5,024,356 A	6/1991	Gerling et al.
	5,029,624 A	7/1991	McCunn et al.
	5,060,701 A	10/1991	McCunn et al.
	5,119,972 A *	6/1992	Reed B65D 23/10 206/509
	5,125,438 A	6/1992	McCunn et al.
	5,220,876 A	6/1993	Monson et al.
	5,224,577 A	7/1993	Falck et al.
	5,301,848 A	4/1994	Conrad et al.
	5,379,812 A	1/1995	McCunn et al.
	5,524,794 A	6/1996	Benede, Jr. et al.
	5,539,669 A	7/1996	Goeckner et al.
	5,551,606 A *	9/1996	Rai B67B 7/28 141/330
	5,638,285 A	6/1997	Newton
	5,641,011 A	6/1997	Benedetti, Jr. et al.
	5,687,782 A	11/1997	Cleveland et al.
	5,737,221 A	4/1998	Newton
	5,740,746 A	4/1998	Ledermann et al.
	5,931,882 A	8/1999	Fick et al.
	5,947,171 A *	9/1999	Woodruff B65D 81/3211 141/354
	5,967,383 A *	10/1999	Hidalgo B65D 47/265 222/548
	6,050,309 A *	4/2000	Woodruff B67D 7/344 141/354
	6,070,539 A	6/2000	Flamme et al.
	6,085,809 A *	7/2000	Woodruff B65D 81/3211 141/351
	6,122,581 A	9/2000	McQuinn

(74) Attorney, Agent, or Firm — Lawrence N. Ginsberg

(57) CLAIM

The ornamental design for a container for dry products, as shown and described.

DESCRIPTION

FIG. 1 is a top, front, left side perspective view of the container for dry products, showing our new design;

FIG. 2 is a bottom, front, right side perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof; and,

FIG. 8 is a right side elevation view thereof.

1 Claim, 5 Drawing Sheets
